Attest:

UNITED STATES PATENT OFFICE.

JOSEPH SALOMON, OF CHICAGO, ILLINOIS.

CHAIR-BACK ADJUSTMENT.

No. 901,559.

Specification of Letters Patent.

Patented Oct. 20, 1908.

Application filed August 14, 1905. Serial No. 274,028.

To all whom it may concern:

Be it known that I, JOSEPH SALOMON, a citizen of the United States of America, and a resident of the city of Chicago, in the county of Cook and State of Illinois, have invented a certain new and useful Improvement in Chair-Back Adjustments, of which the following is a specification.

My invention relates to adjustable backs 10 for use on typewriter chairs, music stools and the like.

The objects of my invention are to provide a comfortable and substantial back for such furniture, which can be readily adjusted to suit the convenience or fancy of the user, and one which is simple in construction and cheap to produce.

The principles of my invention are illustrated in the drawings, in which—

20 Figure 1 shows a side view of a bookkeeper's or typewriter's chair having my improved adjustable back attached thereto. Fig. 2 is a rear view of a clamp for vertical adjustment taken on the line 2—2 of Fig. 3—25 Fig. 3 is a bottom view of the horizontal slide and guides therefor—Fig. 4 is a section of Fig. 3 on the line 4—4.

Further describing my invention by reference to the drawings, in which like characters of reference denote like parts throughout: Fig. 1 shows a stool, having the legs 5, leg connections 6, foot rest 7, and seat 8. The latter should preferably be made of a solid piece of wood flat on the underside, to 35 which is attached the device for horizontal adjustment of the back. This is preferably made of angle iron. One of the legs of the slide is mitered as shown at 11 to form a flange 12 lying parallel with the under side of 40 the seat. The joints may be brazed at the miter and the whole further strengthened by the tie bar 13, which connects the down-turned legs which form flanges 14 standing at right angles to the bottom of the chair 45 seat. Guides 15 adapted to engage the horizontal flanges of the slide may be off-set from a single piece of metal having the body 16 which is attached by screws 17 to the bottom of the chair seat. When the several 50 parts are put in the relation to each other shown in the drawings, the slide 10 will move freely backward and forward in the guides 15, but can be controlled in such movements and be securable at any desired 55 point by the thumb screw 18. The dependent flange forming the rear portion 20 of the

slide provides the stationary portion of a clamp of which the movable portion or jaw 21 is the other. This should be formed of a piece of flat iron having a series of transverse flutings 22 which correspond to the vertical wires 25 which support the back rest 26. The clamp 21 may be held in place by the adjusting screw 32. Sidewise displacement of the back wires and the clamping means therefor may be prevented by the pins or guides 27 which pass through the movable and stationary members of the clamp thus described. The combination of curved and flat surfaces described and which thus embrace the vertical wires of the back bearing upon each other in the manner described, give a high degree of friction and secure attachment against displacement in use.

I claim and desire to secure by Letters Patent the following:

1. In combination with a chair seat and back comprising rods or wires; a slide having a vertical plane flange and horizontal flanges, a clamp comprising a grooved free member 80 to secure the back wires to the vertical flange, guides independent of the clamp securing means to secure said clamp in proper relation to the vertical flange, and guideways on the seat to engage the horizontal flanges. 85

2. In a chair back adjustment a slide independent of the seat comprising vertical and horizontal flanges and a tie bar to connect the front ends of the vertical flanges.

3. In a chair back adjustment, a slide comprising vertical flanges, horizontal flanges mitered together substantially at the rear portion, and a tie bar to connect the front ends of the slide.

4. In a chair back adjustment, a slide 95 having vertical flanges, horizontal flanges mitered together at the rear portion, a clamp for the back wires comprising a free member, and means for adjustably securing the same to the rear portion of the slide.

5. In a chair back adjustment, a slide having vertical flanges, horizontal flanges mitered together at the rear portion, a clamp for the back wires comprising a transversely fluted free member, and means for adjustably securing the same to the rear portion of the slide.

6. In a chair back adjustment, a slide formed of angle iron, one leg of such iron being mitered to form horizontal flanges, and 110 the other leg being bent to form continuous flanges.

7. In a chair back adjustment, a slide formed of angle iron, one leg of such iron being mitered to form horizontal flanges, and the other leg being bent to form continuous depending flanges, and a tie bar to connect the ends of said slide.

8. In a chair back adjustment, the combination with a slide formed of angle iron, one leg of such iron being mitered to form horizontal flanges and the other leg being bent to form a continuous depending flange; of a back clamping jaw, and means for adjustably attaching the same to the depending flange.

9. In a chair back adjustment, the combination with a slide formed of angle iron, one leg of such iron being mitered to form horizontal flanges and the other leg being bent to form a continuous depending flange; of a

transversely fluted back clamping jaw, and means for adjustably attaching the same to the depending flange.

10. In a chair back adjustment, a slide formed of angle iron, one leg of said iron being shaped to form horizontal flanges, and the other leg thereof being bent so that the central portion is adapted to act as one member of a back clamping device while the end portions provide vertical stiffening flanges.

In witness whereof, I have hereunto subscribed my name this 3rd day of August A. D. 1905, in the presence of two subscribing witnesses.

JOSEPH SALOMON.
